UNITED STATES PATENT OFFICE.

JAMES WILLIAM PETTERD, OF CAULFIELD, VICTORIA, AUSTRALIA, ASSIGNOR OF
ONE-HALF TO LANCELOT JAMES WATSON, OF MELBOURNE, AUSTRALIA.

ROLLER-GRAVE STOKER.

Application filed May 5, 1923. Serial No. 687,015.

To all whom it may concern:

Be it known that I, JAMES WILLIAM PETERD, a subject of the King of Great Britain and Ireland, and residing at 118 5 Bambra Road, in the city of Caulfield, in the county of Bourke, State of Victoria, Commonwealth of Australia, have invented certain new and useful Improvements in a Roller-Grate Stoker, of which the following is a specification:

This invention relates to relatively fixed rotating roller grate stokers and has for its objects to provide improved means for driving said rollers; to provide a simple inexpensive construction whereby an auxiliary current of air may be allowed to enter the fire chamber over the fire in starting up the fire or at such other times as may seem advantageous; and to provide an improved ash receiver and ejector, all of which objects, among others, are accomplished by the construction, combination and arrangement of parts, all as hereinafter more particularly set forth, described and claimed.

25 Referring to the drawings:

Figure 1 is a side elevation showing the feed hopper and a portion of the front of a furnace.

Figure 2 is a front elevation of approximately one half of the furnace.

Figure 3 is a diagrammatic plan of a series of driving rollers adapted to frictionally rotate a series of fuel conveying rollers, which are omitted from this view.

35 Figure 4 is a part sectional diagrammatic view of the fuel conveying rollers and the friction rollers driving the same.

Figure 5 is a plan of the fuel conveying rollers.

40 Figure 6 is a sectional view of a fuel conveying ring or roller section.

Figure 7 is a side elevation; and

Figure 8 an edge elevation of a fuel conveying ring or roller section.

45 The invention includes a series of driving rollers 2 mounted upon transverse shafts 3 and rotated by worm gear 4 or the like from a longitudinal driving shaft or shafts 5. The shaft 5 may be provided with a speed cone 6 and be rotated through any suitable gearing. The shafts are mounted in any suitable bearings. The rollers 2 may be either plain or corrugated and their position in relation to each other may be varied from that shown. The rollers may be built

up by a number of rings or sections placed upon and spaced apart upon the shafts 3 if desired. They all rotate in the same direction.

Resting upon the driving rollers 2 and 60 frictionally rotated thereby is a series of fuel conveying rollers. These are preferably corrugated and may be built up upon transverse shafts 7 by rings or sections 8, or the like, suitably spaced apart, if desired. 65 By building up the rollers 8 with rings or sections the width of the furnace may be readily accommodated. The corrugated formation also provides an increased grate area. The rollers 8, further, may be rotated or driven direct or positively instead of frictionally, if desired. Each roller section 8 may be hollow and have formed therein a series of air spaces indicated at 9 whereby the air supply passing between the 70 rollers 2 passes to the fuel through the rollers supporting it and is heated in transit. From Figures 6, 7 and 8 it will be seen that the corrugation or periphery of each section 8 is united by spokes 10 to a divided 75 boss 11 having incuts or recesses 12. Each section therefore only bears upon its shaft 7 at the corners 13. Division of the boss and the provision of the recesses 12 and the general construction of the roller sections 85 provide for lateral expansion under the heat of the furnace. The shafts 7 need not necessarily be of square or similar conformation. And obviously the roller sections need not be provided with specific spokes. 90 The air spaces or openings 9 in the roller sections may be of increased area in the rollers located at the middle of the furnace, in order to provide or introduce a greater volume of air where the fire is fiercest. Any 95 well known means may be used to regulate the delivery of air to any part of the grate such as dampers and a partitioned air box or conduit, dependent upon the furnace construction. The arrangement of the rollers 100 2 and 8 may be such that those at the feed end of the furnace rotate at a faster speed than those at the delivery or ejector end. Under normal conditions the rollers located at or near the delivery end of the furnace 105 grate rotate at a slower speed than those situated at the receiving end and the middle of the grate. The fire is more intense or is fiercest at or near the middle of the furnace and the fuel may be passed through 110

more quickly or be provided with more air accordingly. The speed of the rollers may be varied through the mechanical agency by which they are rotated, according to circumstances, and with the object of maintaining an even thickness or layer of fuel during consumption.

Above the front or feed end of the stoker is a fuel hopper 14 or the like having a sliding control door 15 operated by worm or toothed gearing 16 and a handle 17 or the like. Located at the bottom of the hopper is a roller or rollers 18. This may be driven in any well known way or it may be separately or manually or otherwise rotated.

Adjacent the feed or supply roller 18 is a hinged flap 19 or the like to provide an air supply for starting up the fire and admitting an auxiliary supply of air over the fire when necessary.

An indicator 20 may be used to show the position of the flap 19. The front of the furnace is also provided with a door 20 having inspection openings indicated at 21. These are closed by a suitable rotary shutter or disc operated by a hand knob 22. Any other suitable inspection means may be used.

Disposed at the rear end of the series of rollers 8 is an ejector 23. This may be built up laterally by a series of rings or sections to interengage with the end fuel carrying rollers. The ejector may comprise a plurality of pockets indicated at 24 between which are circumferential closing or roller engaging faces 25.

With this invention the fuel is positively fed from the hopper 14 to the rotating rollers 8 at the feed or front end of the furnace. The rollers 8 pass the bank of fuel into the furnace towards the rear thereof and over or upon succeeding rollers 8. The fuel bank spreads or thins outwardly as it moves onward and by the heat of the furnace the particles cohere causing the mass to rest upon crowns of the corrugations of the rollers 8 as it proceeds. It will be seen that the corrugations of the rollers carried by each shaft 7 alternate or interengage with those of the succeeding shaft. It will also be seen that air spaces or combustion chambers, indicated at 26, are formed below the fuel and in depressions between corrugations. Air entering between the driving rollers 2 encounters the heated fuel

carrying rollers 8 and passing therethrough is thoroughly heated before it enters the spaces 26 and encounters the fuel bridging the crowns of the corrugations. The air also serves to cool the rollers. Although the smaller particles of fuel matte or clinker under the influence of the heat the inter-engaging or staggered arrangement of the corrugated rollers is such that the fuel is sufficiently agitated or broken to ensure efficient combustion. The heated air supply is direct. When the ejector is reached the fuel has been consumed and the ashes are delivered from the last group of rollers 8 into the pockets 24 of the rotating ejector. The circumferential faces 25 ensure that the ashes enter the pockets and are delivered therefrom where desired. A chain, screw or other conveyor of any suitable and known type may be provided beneath the rollers in some types of boilers, such as Cornish and marine types to receive the ashes and discharge them at the front of the boiler.

As beforementioned the basis of the invention is a series of rollers to deliver or carry the fuel through the furnace but substantial novelty is believed to reside in the variation of the speed of the rollers to improve combustion and to more positively prevent matting of other than small particles of the fuel, and in variation of the air supply to ensure complete consumption.

I claim:—

A roller grate stoker comprising a plurality of grate rolls relatively fixedly mounted with relation to each other, in combination with means for rotating said rolls, said means comprising a plurality of shafts arranged in a single plane and each provided adjacent its central portion with a small gear wheel, and adjacent each end with a larger drive wheel, whereby each shaft will carry driving means equally engaging with the ends of the grate rolls respectively, said gear wheels of all said shafts being aligned in a direction transverse of said shafts, and a drive shaft carrying driving means intermeshing with said respective gears to positively drive all of said shafts simultaneously.

In testimony whereof, I have signed my name to this specification.

JAMES WILLIAM PETTERD.
